UNITED STATES PATENT OFFICE.

FREDERICK RATCLIFF, OF NEW BEDFORD, MASSACHUSETTS, ASSIGNOR TO
THE PAIRPOINT MANUFACTURING COMPANY, OF SAME PLACE.

DESIGN FOR A PRONGED STANDARD.

SPECIFICATION forming part of Design No. 23,182, dated April 10, 1894.

Application filed October 5, 1893. Serial No. 487,292. Term of patent 7 years.

To all whom it may concern:

Be it known that I, FREDERICK RATCLIFF, a citizen of the United States, residing in New Bedford, in the county of Bristol and State of Massachusetts, have invented and produced a new and original Design for a Pronged Standard for Toilet Articles, of which the following is a specification, reference being had to the accompanying drawing, showing a perspective view of the same.

The leading feature of my design consists

of an upright body having a concave head formed with radial projections.

A is the upright body, B the concave head, b the radial projections. 15

What I claim is—

The design for a pronged standard for toilet articles herein shown and described.

FREDERICK RATCLIFF.
